L. W. Campbell,

Piston Packing.

No 70,522.

Patented Nov. 5, 1867.

United States Patent Office.

LUTHER W. CAMPBELL, OF AURORA, ILLINOIS, ASSIGNOR TO HIMSELF,
A. T. HALL, C. F. ALLEN, AND A. J. AMBLER.

Letters Patent No. 70,522, dated November 5, 1867.

IMPROVEMENT IN PISTON-PACKING.

The Schedule referred to in these Letters Patent and making part of the same.

TO ALL WHOM IT MAY CONCERN:

Be it known that I, LUTHER W. CAMPBELL, of Aurora, in the county of Kane, and State of Illinois, have invented a new and useful Improvement in Elastic Metallic Packing for the Piston-Heads of Steam Engines; and I do hereby declare that the following is a full, clear, and exact description of the same, reference being had to the annexed drawings, making part of this specification, in which—

Figure 1 is a side elevation.

Figure 2, a vertical longitudinal section.

Figure 3 is a plan, and

Figure 4 is a vertical transverse section.

The same letters in all the figures indicate parts which are identical.

This improvement is in the arrangement of a double conical central ring around a fixed hub upon the piston-rod, around which is placed a series of concentric rings, so adjusted that the packing-rings upon each end of the piston-head shall be alternately expanded by the pressure of the steam, as it is received into the opposite ends of the cylinder, acting against rings with inclined faces; and the nature of my invention will appear from the following description and claims.

In the drawings, A is a central hub, attached to and forming part of the head B, both of them being rigidly attached to the piston-rod C. The head B' is attached to the hub by bolts D entering the radial arms at D'. On the radial arms of the central hub is placed a ring, E, constructed with a central flange, E¹, projecting from its periphery, the ring being cut away in both directions from the base of the flange on the periphery, so as to form the double conical faces shown at E² in fig. 2. Around the ring E, on each side of the central flange E¹, are elastic rings F, the inner faces of which are inclined, to correspond with the inclined faces E², and the exterior faces are parallel with the bore of the cylinder. Around the rings F are thin rings G, used for the purpose of breaking joints, so as to prevent the steam from passing through the rings, which are cut so as to give them expansibility. Around the rings G are two rings H H, which, bearing against the inner surface of the cylinder, form an elastic metallic packing for the piston-head.

Recesses are cut in the heads B and B', to receive the edge of the rings F, and into these recesses a series of holes, J J, is bored through the heads, to permit the steam to enter; which, as it is admitted alternately to the two ends of the cylinder, pressing against the edges of the rings F, will force them on to the faces E² of the ring E, thus expanding them, and pressing them outwardly, so as to force the packing-rings against the cylinder.

What I claim as my invention, and desire to secure by Letters Patent, is—

1. So arranging a double series of concentric elastic rings, F, G, and H, that, acting in combination with the central ring E, having double inclined faces E², they may, by the pressure of the steam, alternately admitted to the opposite ends of the cylinder, be alternately expanded, substantially in the manner and for the purpose set forth.

2. The combination of the hub A, perforated plates B B', ring E, having a central flange, E¹, and double inclined faces E², and the concentric rings H, G, and F, constructed and arranged to operate substantially as set forth.

In testimony whereof I have hereunto set my hand in the presence of two subscribing witnesses.

L. W. CAMPBELL
